UNITED STATES PATENT OFFICE.

FREDERICK LAMPLough, OF LONDON, ENGLAND.

CONDENSER.

SPECIFICATION forming part of Letters Patent No. 718,851, dated January 20, 1903.

Application filed September 30, 1902. Serial No. 125,357. (No model.)

To all whom it may concern:

Be it known that I, FREDERICK LAMPLough, a subject of the King of Great Britain, residing at London, England, have invented a new 5 and useful Condenser, of which the following is a full, clear, and exact description.

The invention relates to an improved construction of condenser whereby very effective condensation is obtained.

10 I will describe my invention by the aid of the accompanying drawings, in which—

Figure 1 is a longitudinal section of the condenser through one of the main tubes. Fig. 2 is a side elevation; Fig. 3, an end elevation, and Fig. 4 an inner end view of one 15 of the hollow rings separately.

According to my invention I employ a series of main tubes *a*, each of which is surrounded at each end by tubes or cones *b*, communicating with a central chamber *c*, through which the series of tubes *a* pass. Flattened cross-tubes *d* are fixed within the main tubes *a* and communicate with the spaces surrounding said main tubes.

20 At one end of each main tube *a* is a hollow ring *e*, formed with a conical mouth *e'* and having a ring *e''* of small holes around the inner end of said conical mouth. The outer portion of the hollow ring is connected to the 25 narrow end of the cone *b* and the inner portion to the main tube *a*. A port *b'* opens from the bottom of the space between each of the main tubes *a* and the surrounding tubes or cones at one end thereof to allow of the passage of steam into the interior of the hollow 30 rings *e*.

f is an inlet to the chamber *c* for the exhaust-steam.

The exhaust-steam on entering the central 40 chamber *c* and spaces surrounding the main tubes *a* for the first time mostly condenses and passes through the ports *b'* into the hollow rings *e*, whence it is ejected through the rings of holes *e''*. At the same time through 45 the velocity of the exhaust a large quantity of air is propelled through the tubes *a*, which

becoming mixed with the escaping water and aqueous vapor of condensation causes a further condensation of the vapor and distributes the cooled water upon the surface of the 50 cross-tubes *d*, which latter, although shown at right angles to each other, are preferably arranged in the form of a spiral. The action of the induced current of air upon the wetted surface of the cross-tubes *d* causes a further 55 reduction in temperature, which is communicated through the cross-tubes *d* and main tubes *a* to the interior or exhaust space, thus cooling the exhaust-steam and making more water of condensation to keep the apparatus 60 going, so that after the first start the action is continuous.

What I claim as my invention, and desire to secure by patent, is—

1. In a condenser, the combination of a series of main tubes, a chamber surrounding the central portion of such main tubes, a steam-inlet to such chamber, tubes or cones surrounding the projecting ends of the main tubes, flattened cross-tubes fixed within the 70 main tubes and communicating with the surrounding space, a hollow ring with a conical mouth at one end of each main tube, a port in the bottom of the space surrounding said main tube and opening into the hollow ring, 75 and a ring of holes in the interior of the hollow ring, substantially as herein set forth.

2. In a condenser, the combination of a series of main tubes, a chamber surrounding said main tubes, flattened cross-tubes within 80 the main tubes, and jets from the spaces surrounding the main tubes directing the partially-condensed steam through the main tubes and onto the flattened cross-tubes, substantially as herein set forth and for the purpose explained.

In testimony whereof I affix my signature in presence of two witnesses.

F. LAMPLough.
